UNITED STATES PATENT OFFICE

147,500

DESIGN FOR A CONTAINER FOR A TOY

T. Barry Hodge, Chicago, Ill.

Application November 29, 1945, Serial No. 124,196

Term of patent 3½ years

(Cl. D58—12)

To all whom it may concern:

Be it known that I, T. Barry Hodge, a citizen of the United States of America, residing at Chicago, in the county of Cook and State of Illinois, have invented a new, original, and ornamental Design for a Container for a Toy, of which the following is a specification, reference being made to the accompanying drawing, forming a part thereof.

Fig. 1 is a top and side perspective view of a container for a toy, showing the ornamental design on two sides thereof;

Fig. 2 is a view of the back side of said container not shown in Fig. 1, showing the ornamental design on the back side;

The bottom of the container is plain and the end not shown is open like that shown in Fig. 1.

I claim:

The ornamental design for a container for a toy, substantially as shown and described.

T. BARRY HODGE.
